SAWING MACHINE

Edwin Robert Evans and John Henry Walter
Evans, Hamilton, Ontario, Canada

Application August 12, 1950, Serial No. 179,032

3 Claims. (Cl. 29—69)

1

Our invention relates to a machine for cleaning reclaimed concrete form boards or panels, and the object of the invention is to provide a machine wherein used concrete form boards or panels may be reconditioned for further use in the construction of concrete forms. General practice in the construction industry has been to scrap concrete form boards after they have been removed from the set concrete, and to use new lumber in the construction of forms. This practice was not considered to be particularly wasteful when lumber was abundant and cheap, but due to today's scarcity of lumber and high prices, it is realized that the scrapping of used form boards adds considerably to concrete construction costs and also very frequently delays construction due to the difficulty in obtaining new lumber.

A particular object of the present invention is to devise a simple and effective machine through which used concrete form boards may be passed for reclaiming, and wherein protruding nails in the boards may be readily severed and the boards thoroughly cleaned of adhering concrete whereby they are put into condition for re-use.

Another object of the invention is to provide board flattening or squeezing rollers in the machine so that the nails may be cut off close to the board surface and the faces of the boards thoroughly scrubbed and cleaned irrespective of any warps developed in the boards due to exposure of their inner faces to wet concrete.

A further object of our invention is to provide a simple machine consisting of a frame supporting a plurality of pairs of upper and lower rollers and rotary scrubbing brushes through which a board may be passed for reclaiming; a high speed circular saw being supported in the frame and positioned to engage nail ends hanging from the board and cut them off.

With the foregoing and other objects in view as shall hereinafter appear, our invention consists of a concrete form board or panel cleaning machine, all as hereinafter more particularly described and illustrated in the accompanying drawings in which:

Fig. 1 is a plan view of the machine.

Fig. 2 is a vertical longitudinal cross-sectional view through the machine, being taken through the line 2—2, Fig. 1.

Fig. 3 is an enlarged transverse cross-sectional view through the machine, being taken through the line 3—3, Fig. 1.

Fig. 4 is an enlarged transverse cross-sectional view through the machine, being taken through the line 4—4, Fig. 1, and

2

Fig. 5 is an enlarged side elevational view of a fragmentary portion of the machine, being taken from the line 5—5, Fig. 1.

Like characters of reference indicate corresponding parts in the different views of the drawings.

The machine broadly comprises a plurality of pairs of upper and lower rollers, a nail cutting saw and a pair of scrubbing rollers, all of which are supported in horizontal alignment upon a frame 2 of such a height that the boards may be conveniently passed through the machine by the operator.

The board feed end of the frame 2 carries a pair of spaced-apart parallel channel guide members 3 between which a board may be fed into the machine, as illustrated in Fig. 4. In order to permit the distance between the channels 3 to be adjusted to various board widths, a pair of threaded spindles 4 are mounted within bearings 5 in the vicinity of the upper edges of the frame 2. Each of the spindles 4 is formed with two threaded portions 6 and 7 at either end thereof, the threads 6 being right-hand threads and the threads 7 being left-hand threads. The guide channels 3 are carried upon two pairs of screw blocks 8 which are mounted upon the threaded portions 6 and 7 of the spindles 4, whereby rotation of the spindles 4 in one direction will move the blocks 8 and channels 3 towards each other and rotation of the spindles 4 in the opposite direction will move the blocks 8 and channels 3 apart.

In order that the screw blocks 8 may move in unison upon rotation of the spindles 4, two sprocket wheels 9 of equal diameter are mounted upon the ends of the spindles 4 and are connected by an endless chain 10. One of the spindles 4 carries an operating handle 11 upon its end opposite to the end carrying the sprocket wheel 9. It will be understood that upon rotation of the handle 11 the operator may either move the guide channels 3 towards each other or apart to suit the width of the boards being passed between the channels.

To carry a board into the machine, a pair of feed rollers 12 and 13 are suitably mounted and positioned upon the frame 2 at the inner end of the channel guide assembly. The roller 13, as illustrated in Fig. 3, consists of a shaft 14 carrying a plurality of equal diameter roller flanges 15 which are adjustably secured in any suitable manner upon the shaft 14 as by locking screws 16. The outer flanges 15 are formed with lips 17 which act as guides in directing a board 18 between the rollers. The roller shaft 14 carries

a sprocket wheel 19 on one end thereof and over which a drive chain 20 passes.

As used form boards generally carry a number of nails which remain in the board after it is pulled out of placed in taking down a concrete form, the purpose of providing a board guide consisting of two channels and lower rollers of flange form will be readily apparent upon reference to Figs. 3 and 4. The channels 3 are so proportioned that they only overlie the edges of the board 18 to a slight degree so as to clear the nails 21 which are usually spaced in from the edges of a board, and the flanges 15 are so arranged upon the shaft 14 that the nails will pass between the flanges as the board passes through the feed rollers.

A second pair of rollers 22 and 23 are adjacently positioned to the feed rollers 12 and 13 and are of the same construction and arrangement, except that the roller 23 is not driven. The rollers 22 and 23 are provided for the purpose of flattening a warped board, such as illustrated in Figs. 3 and 4, and for this purpose are spaced apart a distance substantially equal to the thickness of a board.

A circular saw 24 is positioned adjacently to the pair of rollers 22 and 23 and is arranged to lie in close proximity to the bottom face of a board passing thereover. The saw is carried upon the upper end of a shaft 25 mounted within a pair of bearing blocks 26 and driven by a motor 27 through the medium of a drive belt 28 extending around a pair of sprockets 29 and 30 on the motor shaft and saw shaft 25. The circular saw is designed to rotate at a high speed and cut off any nails 21 protruding downwardly from a board passing thereover.

Another pair of board squeezing or flattening rollers 31 and 32 are carried upon the frame to receive the board after it passes over the nail cutting saw 24 for the purpose of retaining a warped board in its flattened form as it passes over the saw to be directed between the scrubbing brushes.

The board cleaning assembly is adjacently positioned to the rollers 31 and 32 and consists of a pair of rotary scrubbing brushes 33 and 34 which are carried upon spindles 35 and 36. The spindle 35 is mounted within a pair of bearing blocks 37 carried within bearing block frames 38 extending upwardly from the frame 2. The spindle 36 of the brush 34 is carried within a pair of bearing blocks 39 secured to the under sides of the top members of the frame 2. The spindles 35 and 36 carry gear wheels 40 and 41 which mesh with a suitably mounted gear wheel 42 positioned therebetween. The spindle 36 also carries a sprocket wheel 43 over which a drive chain 44 passes. It will be apparent that rotation of the scrubbing brush 34 and its spindle 36 will, through the medium of the gears 40, 41 and 42, rotate the scrubbing brush 33.

To feed a finished board from out of the machine, a pair of rollers 45 and 46 are mounted upon the frame 2 adjacent to the scrubbing brushes, the spindle 47 of the lower roller carrying a sprocket wheel 48 over which a drive chain 49 is carried. In order to prevent a board from tipping up as it leaves the machine a pair of freely rotatable rollers 50 and 51 may be mounted upon the frame 2 if found desirable.

To provide for alteration of the spacing of the rollers of each pair in relation to the thickness of a board being fed through the machine, the upper roller of each pair of rollers is mount-

ed for vertical adjustment. The spindles of the upper rollers are carried within bearing blocks 52 which are slidably mounted within inverted U-shaped frames 53 carried upon the upper edges of the frame 2. The blocks 52 are urged upwardly within the frames by compression springs 54 inserted between the lower faces of the blocks 52 and the top edges of the frame 2. Adjusting screws 55 are threaded into the top cross members of the frames 53 to bear against the upper faces of the bearing blocks 52.

In moving the rollers closer together the adjusting screws 55 are threaded downwardly whereby the bearing blocks 52 are moved downwardly against the compression of the springs 54. To move the blocks apart the adjusting screws 55 are threaded upwardly to allow the compressed springs 54 to push the bearing blocks 52 upwardly.

The machine driving rollers and saw may be driven in any suitable manner, as for example, that shown in the drawings, wherein we furnish two motors, one motor for driving the rollers and a second motor 27, as hereinbefore described, for driving the saw.

The roller drive comprises a motor 56 coupled to a speed reduction and drive reversing gear box 57. The gear box is designed to incorporate a pair of drive shafts which rotate in opposite directions. Referring to Fig. 5, one drive shaft 58 is contained within a second hollow drive shaft or sleeve 59 which rotates in the opposite direction to the shaft 58. The drive chain 44 extending from the sprocket 43 of the scrubbing brushes extends over a sprocket wheel 60 secured to the drive shaft 59.

The drive shaft 58 protrudes outwardly from the hollow end of the drive shaft 59 and upon which a pair of sprocket wheels are mounted. One sprocket wheel carries the chain 20 which extends to the sprocket 19 of the lower feed roller 12, and the other sprocket wheel carries the chain 49 extending to the sprocket wheel 48 of the roller 46. It will thus be appreciated that through this arrangement the scrubbing brushes 33 and 34 rotate in the opposite direction to the driving rollers whereby the brushes rotate against the movement of the board passing therebetween.

In adjusting the machine, the guide channels 3 are arranged such a distance apart that a board may freely slide therebetween. The roller 12 of the feed rollers 12 and 13 is adjusted in height so that a board may be readily fed between the rollers by the operator. The board flattening rollers 22 and 31 of the pairs of rollers 22 and 23 and 31 and 32 are so adjusted in height that the distance between the faces of the rollers of each pair is substantially equal to the thickness of the board to be received, so that a warped board, such as illustrated in Figs. 3 and 4, in passing between these pairs of rollers is flattened whereby the circular saw may be adjusted to sweep across the lower face of the board passing thereover, and the scrubbing brushes to engage the board passing therethrough across its entire width.

It will thus be apparent that we have devised a very simple type of machine which may be readily set up at the site of a building construction, and wherein used concrete form boards may be readily and quickly passed therethrough for reclaiming, the treating of each board being only a matter of seconds. Although we have shown and described our machine as being designed for treating concrete form boards it will be appreciated

ciated that it may be readily proportioned to treat and reclaim form panels in the same manner as the boards, and while we have shown and described a particular embodiment of our invention, it is to be understood that we may make such changes and alterations as we may from time to time deem necessary, without departing from the spirit of our invention as set forth in the appended claims.

What we claim as our invention is:

1. A machine for reclaimed nail containing concrete form boards and comprising a frame supporting a plurality of pairs of upper and lower rollers between which a board may be passed for reclaiming and a source of power for rotating several of the rollers, one pair of rollers constituting the means for feeding a board therebetween into the machine and having one of its rollers driven from the source of power, one of the said board feeding rollers being formed with a plurality of board face engaging flanges, a second pair of rollers constituting the means for flattening a board and adjacently positioned to the board delivery side of the feed rollers and having their rolling faces spaced apart a distance substantially equal to the thickness of the board to be received therebetween whereby the faces of said rollers engage the entire widths of the upper and lower faces of the board, and a circular nail severing saw driven from the source of power and positioned adjacently to the board flattening rollers at the board delivery side thereof, the circular saw being positioned to lie in close proximity to the bottom face of a board passing thereover.

2. A machine for reclaimed nail containing concrete form boards and comprising a frame supporting a plurality of pairs of upper and lower rollers between which a board may be passed for reclaiming and a source of power for rotating several of the rollers, one pair of rollers constituting the means for feeding a board therebetween into the machine and having one of its rollers driven from the source of power, one of the said board feeding rollers being formed with a plurality of board face engaging flanges, a second pair of rollers constituting the means for flattening a board and adjacently positioned to the board delivery side of the feed rollers and having their rolling faces spaced apart a distance substantially equal to the thickness of the board to be received therebetween whereby the faces of said rollers engage the entire widths of the upper and lower faces of the board, a circular nail severing saw driven from the source of power and positioned adjacent to the board flattening rollers at the board delivery side thereof, the circular saw being positioned to lie in close

proximity to the bottom face of a board passing thereover, a second pair of board flattening rollers positioned to receive a board in its travel upon passing out of contact with the nail severing saw.

5 3. A machine for reclaimed nail containing concrete form boards and comprising a frame supporting a plurality of pairs of upper and lower rollers between which a board may be passed for reclaiming and a source of power for rotating several of the rollers, one pair of rollers constituting the means for feeding a board therebetween into the machine and having one of its rollers driven from the source of power, one of the said board feeding rollers being formed with a plurality of board face engaging flanges, a second pair of rollers constituting the means for flattening a board and adjacently positioned to the board delivery side of the feed rollers and having their rolling faces spaced apart a distance substantially equal to the thickness of the board to be received therebetween whereby the faces of said rollers engage the entire widths of the upper and lower faces of the board, a circular nail severing saw driven from the source of power and positioned adjacently to the board flattening rollers at the board delivery side thereof, the circular saw being positioned to lie in close proximity to the bottom face of a board passing thereover, a third pair of board flattening rollers positioned to receive a board in its travel upon passing out of contact with the saw, and a fourth pair of rollers positioned to receive a board passing out of contact with the third pair of board flattening rollers and deliver it from the machine.
